CHAIR

Ralph K. Merrill, Grand Rapids, Mich., assignor
to American Seating Company, Grand Rapids,
Mich., a corporation of New Jersey

Application September 25, 1931
Serial No. 565,075

2 Claims. (Cl. 155—194)

The present invention relates to chairs and more particularly to metal chair constructions.

The main objects of the invention are to provide a novel form of chair construction; to provide a metal chair construction which may be conveniently assembled from a few parts; to provide a chair which is light in weight but of a rigid and sturdy construction; and, to provide a metal school chair which is economical to manufacture and which is practical in use.

An illustrative embodiment of the invention is shown in the accompanying drawing, wherein:

Figure 1 is a sectional view of the chair taken on line 1—1 of Figure 2;

Figure 2 is a sectional view thereof taken on line 2—2 of Figure 1;

Figure 3 is an enlarged sectional view showing a portion of the drawer and one drawer guide; and

Figure 4 is a sectional view taken on line 4—4 of Figure 2.

Referring to the drawing in which like parts are designated by the same numerals in the several views, a pair of front legs 1, of angle iron construction are bowed outwardly at their floor-contacting ends and a portion of the metal is turned inwardly and upwardly to form feet 2.

A pair of rear legs 3, likewise of angle iron construction are provided with similarly formed feet 4 and are longer to provide a chair back which is formed by a pair of parallel spaced back supporting members 5, 6 which are riveted or otherwise secured as shown in Figure 2.

A pair of angle iron seat supporting stringers 7, here shown as channel bar members, are secured to each pair of front and rear legs on the respective inner sides of the legs as by spot welding. The upper sides of these stringers are formed to provide supports for the seat 8 which may be secured thereto as by bolts 9.

A pair of reinforcing angle iron stringers 10 are likewise secured to each pair of front and rear legs on the respective inner sides of the legs and below the seat supporting stringers.

In order to provide for a drawer 11, slideable sideways below the seat, a U-shaped integrally formed sheet metal member has its opposite ends 12, 13, here shown as paneled for appearance and strengthening purposes, welded to the inner sides of the front and rear angle iron legs and the medial portion 14 thereof is provided with embossed reinforcing ribs 15 and is welded to the under side of the angle iron reinforcing stringers. A drawer support is thus provided and drawer guides 16 are likewise formed therein where-

by the drawer 11 may be slid sideways in and out of its support below the seat.

The metal seat with its drawer support and drawer herein shown and described is particularly adapted for use in schools and because of its light weight is easily portable yet is rigid and sturdy in construction.

The angle iron seat supporting stringers 7 may be referred to as upper longitudinally extending stringers while the reinforcing angle iron stringers 10 may be referred to as lower longitudinally extending stringers. These upper and lower stringers constitute seat side frame members and are vertically spaced so as to provide a receiving space therebetween for the drawer 11. The U-shaped integrally formed sheet metal member may be considered as having opposite upstanding end portions 12 and 13 thereof which in effect provide upstanding transversely extending frame members. The horizontal bottom or bight section of the U-shaped member is as previously indicated medially depressed for the full transverse width thereof and provides the transversely extending drawer guides or slideways 16. These slideways 16 are inwardly located in a longitudinal direction in respect to the upstanding ends of the U-shaped member and it will be noted that they extend upwardly above the lower longitudinally extending angle iron stringer 10. In fact these transversely extending guideway portions 16 are so located in respect to the inner edges of the upstanding legs—1 and 3—that the drawer is readily slideable to and from its position under the seat proper.

While but one specific embodiment of this invention has been herein shown and described, it will be understood that numerous details of the construction shown may be altered or omitted without departing from the spirit of this invention as defined by the following claims.

I claim:

1. In a chair construction having angle iron legs, upper longitudinally extending angle iron seat supporting stringers connecting each pair of front and rear legs, lower longitudinally extending reinforcing angle iron stringers connecting each pair of front and rear legs, and an integrally formed U-shaped member connecting said pairs of legs, having in each upstanding end portion thereof an embossed reinforcing section and in the bight portion a depressed section extending the full width thereof so as to provide transversely extending guideways that extend upwardly in respect to said depressed portion and that are inwardly spaced in a longitudinal direction in re-

spect to the upwardly extending end portions, the opposite upstanding ends of the U-shaped member being welded to the angle iron legs, said medial depressed portion being embossed so as to 5 provide reinforcing ribs, and the opposite side edges of said depressed portion being secured to the lower longitudinally extending reinforcing angle iron stringers in such a manner that the transversely extending guideways extend upwardly above the upper face of said last mentioned stringers.

2. In a chair construction having angle iron legs, angle iron seat supporting stringers connecting each pair of front and rear legs, reinforcing angle iron stringers connecting each pair of front and rear legs, which reinforcing angle iron

stringers are below said seat supporting stringers, and an integrally formed U-shaped member connecting said pairs of legs and whose opposite ends are secured to the angle iron legs and whose medial portion is secured to the reinforcing angle iron stringers, said medial portion being depressed and formed so as to provide transversely extending guides that extend upwardly above the upper face of the reinforcing angle iron stringers and are inwardly spaced in respect to the upstanding end portions of the U-shaped member whereby a drawer may be supported by and slid upon said depressed medial portion and between the guideways thus provided.
